UNITED STATES PATENT OFFICE.

OTTO E. STAACK, OF PORT TOWNSEND, WASHINGTON.

LOCK.

1,242,256.

Specification of Letters Patent.

Patented Oct. 9, 1917.

Application filed June 30, 1917. Serial No. 177,929.

To all whom it may concern:

Be it known that I, Otto E. STAACK, a citizen of the United States, residing at Port Townsend, in the county of Jefferson and State of Washington, have invented certain new and useful Improvements in Locks, of which the following is a specification, reference being had to the accompanying drawings.

10 This invention relates to certain improvements in locks and it is an object of the invention to provide a novel and improved device of this general character adapted to be employed in connection with a controlling lever provided with a latch mechanism including a release lever fulcrumed to the controlling lever and which serves to hold the release lever against movement to prevent unauthorized operation of the controlling lever.

15 The invention consists in the details of construction and in the combination and arrangement of the several parts of my improved lock wherein certain important advantages are attained and the device rendered simpler, less expensive and otherwise more convenient and advantageous for use, as will be hereinafter more fully set forth.

20 The novel features of my invention will hereinafter be definitely claimed.

In order that my invention may be the better understood I will now proceed to describe the same with reference to the accompanying drawings wherein—

25 Figure 1 is a view in elevation of the upper portion of the controlling lever illustrating a lock constructed in accordance with an embodiment of my invention in applied position;

30 Fig. 2 is a sectional view taken substantially on the line 2—2 of Fig. 1; and

35 Fig. 3 is a sectional view taken substantially on the line 3—3 of Fig. 2.

As disclosed in the accompanying drawings C denotes a controlling lever of a type employed in connection with the emergency brake on a Ford automobile and R denotes a release lever fulcrumed on the controlling lever C and which serves to release the well known type of latch. As the lower end portion of the controlling lever C and the latch form no part of my present invention and are well known a disclosure thereof is not believed necessary.

40 My improved lock comprises a body or block 1 adapted to be positioned between the

release lever R and the handle H of the controlling lever C whereby the release lever R is effectively held against inward movement. One edge of the block 1 is grooved as at 2 to receive the handle H while the opposite edge of the block 1 is rounded as indicated at 2^a so as to snugly fit within the upper or free end portion of the release lever R. It is found of advantage to provide the rounded edge 2 with a wear plate 3.

45 Permanently secured to a side face of the block or member 1 as at 4 is a metallic plate or strap 5 extending beyond the opposite edges of the block or member 1 and hingedly connected to one end portion of the plate or strap 5 is a hasp 7 angular in longitudinal section and which is adapted to bridge the handle H of the controlling lever C and overlie the face of the block or member 1 remote from the strap or plate 5. Hingedly engaged with the opposite end portion of the plate or strap 5 is a second hasp 8 also angular in longitudinal section and which contacts with the outer face of the release lever R and is adapted to overlie the free end portion of the hasp 7 when said hasp 7 is operatively engaged with the handle H. The free end or overlying portions of the hasps 7 and 8 are provided with 50 the registering slots 9 through which is adapted to be directed the staple member 10 carried by the block or member 1 when said hasps 7 and 8 are in locked adjustment. A padlock 11 or the like is adapted to be engaged with the staple 10, as illustrated in Fig. 1 for holding the hasps 7 and 8 against outward swinging movement. The face of the block or member 1 with which the hasps 7 and 8 coact is provided with 55 an open ended recess 12 extending slightly below the plane occupied by said hasps 7 and 8 when in closed position. The recesses 12 permits the ready insertion of a digit of the hand inwardly of said hasps 7 and 8 to facilitate the outward swinging movement thereof when it is desired to remove my improved lock from applied position.

60 From the foregoing description, it is thought to be obvious that a lock constructed in accordance with my invention is particularly well adapted for use by reason of the convenience and facility with which it may be assembled and operated and it will also be obvious that my invention is susceptible of some change and modification without materially departing from the appearance

and spirit thereof and for this reason I do not wish to be understood as limiting myself to the precise arrangement and formation of the several parts herein shown in carrying out my invention in practice except as hereinafter claimed.

I claim:

As a new article of manufacture, a lock comprising a body adapted to be inserted between a lever and a release lever fulcrumed thereto, a strap secured to one face of the block and extending beyond opposite ends thereof, hasps pivotally engaged with the extended portion of the straps, each of said hasps being angular in longitudinal section so as to overlie the face of the block remote from the strap and to overlap each other, said hasps being adapted to bridge the lever and the release lever for

holding the body snugly between the lever and the release lever to prevent inward movement of the release lever, the overlying portions of the hasps being provided with slots, a staple member carried by the body and extending through the slots when the hasps are in overlying relation, and means for holding the hasps against outward movement when in closed position, the face of the body remote from the strap being provided with an open ended recess partially intersecting the plane occupied by the hasps when in overlying relation.

In testimony whereof I hereunto affix my signature in the presence of two witnesses.

OTTO E. STAACK.

Witnesses:

EARL A. OATMAN,
CHAS. WARD.
